US0D1009476S

(12) **United States Design Patent** (10) **Patent No.:** **US D1,009,476 S**
(45) **Date of Patent:** **** Jan. 2, 2024**

(54) **MESH BASKET**

(71) Applicant: **Design Ideas, Ltd.**, Springfield, IL (US)

(72) Inventors: **Christopher Hardy**, Springfield, IL (US); **R. Neal Post**, Springfield, IL (US)

(73) Assignee: **Design Ideas, Ltd.**, Springfield, IL (US)

(**) Term: **15 Years**

(21) Appl. No.: **29/718,845**

(22) Filed: **Dec. 30, 2019**

Related U.S. Application Data

(63) Continuation of application No. 29/702,026, filed on Aug. 16, 2019, now Pat. No. Des. 873,567, which is a continuation of application No. 29/627,840, filed on Nov. 30, 2017, now Pat. No. Des. 865,365, which is a continuation of application No. 29/566,795, filed on Jun. 2, 2016, now Pat. No. Des. 807,036, which is a continuation of application No. 29/327,206, filed on Oct. 31, 2008, now Pat. No. Des. 759,976.

(57) **CLAIM**

The ornamental design for a mesh basket, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a mesh basket showing our new design; and,

FIGS. 2-5 are perspectives which are respectively front/rear, sides, top and bottom views thereof.

**1 Claim, 5 Drawing Sheets
(5 of 5 Drawing Sheet(s) Filed in Color)**
